Attorney

UNITED STATES PATENT OFFICE.

EMIL ELSAESSE, OF LANGERFELD, GERMANY, ASSIGNOR, BY MESNE ASSIGNMENTS,
TO THE CHEMICAL FOUNDATION, INC., A CORPORATION OF DELAWARE,

SPINNING VISCOUS LIQUIDS IN FLOWING FEEDING LIQUIDS.

1,414,076.

Specification of Letters Patent. Patented Apr. 25, 1922.

Application filed April 12, 1917. Serial No. 161,632.

(GRANTED UNDER THE PROVISIONS OF THE ACT OF MARCH 3, 1921, 41 STAT. L., 1313.)

To all whom it may concern:

Be it known that I, EMIL ELSAESSE, a citizen of the German Empire, residing at Langerfeld, Westphalia, Germany, have invented certain new and useful Improvements of Spinning Viscous Liquids in Flowing Feeding Liquids, (for which I have filed application in Germany Aug. 25, 1916;) and I do hereby declare the following to be a full, clear, and exact description of the invention, such as will enable others skilled in the art to which it appertains to make and use the same.

My improvement relates to spinning viscous liquids, while flowing liquids are used for feeding the thread.

In the practice, heretofore, of such a process, the feeding liquid, being under reduced pressure, nearly always contains air. As a consequence, it was found that bubbles were present in the feeding or flowing liquid, and that such bubbles have been very disturbing in the formation of the thread from the solution of copper-oxide ammonia cellulose.

It is an object of this invention to use as the feeding or flowing liquid one which contains no gases, and so cannot give off bubbles.

In carrying out my invention, therefore, I remove all the gases (air, for instance, where water is employed) from such liquid before the coagulating process. The removal of such gases may be assured by evacuation, or by heating, or by evacuation assisted by heating. As a consequence, there will be no bubbles in the liquid when used for feeding or flowing the threads.

Owing to the absence of the bubbles, the spinning process is carried out very evenly, and without any breaking of the thread.

In the practice of my process, I may use any suitable apparatus. The accompanying drawing shows (somewhat diagrammatically) an apparatus useful in carrying out the process.

a is a reservoir for the feeding or flowing liquid (water, for instance). b is a pipe leading therefrom and into the upper part of a closed tank, c, which is connected, by

pipe d, with a suitable vacuum pump. f is a pipe leading from the lower part of the tank, to the spinning machine indicated at e.

The liquid is drawn from reservoir a into tank c, and the gases are there drawn off, by the pump, from the liquid. Then the liquid passes, by the pipe f to the spinning machine.

Heat may be applied to the liquid while in reservoir a or in tank c, or at both such points. The heating will assist in driving off the gases.

As tank c is arranged a considerable distance (in practice, thirty feet) above the spinning machines, it follows that a good vacuum will be maintained in the tank, to effect a thorough evacuation of the liquid.

The liquid, freed from bubbles, is delivered into the spinning machines and is there used for the flowing of the threads of the cellulose solution and the coagulation of the same.

What I claim is:

1. In the spinning of a viscous liquid by the aid of another liquid, the steps comprising removing gases and bubbles from the second-named liquid, and afterwards using said liquid as the coagulating and flowing bath for assisting the flowing and formation of threads of the viscous liquid.

2. In the spinning of a viscous liquid by the aid of another liquid, the process which consists in subjecting the second-named liquid to the action of a vacuum to remove gases and bubbles therefrom, and afterwards using said liquid as the coagulating and flowing bath for assisting the flowing and formation of threads of the viscous liquid.

3. In the spinning of a viscous liquid by the aid of another liquid, the steps comprising removing gases and bubbles from the second-named liquid, and afterwards using said liquid for assisting the flowing and formation of threads of the viscous liquid.

In testimony whereof I hereunto affix my signature in the presence of two witnesses.

EMIL ELSAESSE.
